UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 13, 1924, Serial No. 699,057. Renewed June 3, 1929.

My invention relates to mining machines. It has for its object to provide an improved mining machine, and more particularly to provide an improved feeding mechanism for such a machine whereby feeding operation is facilitated and the feeding mechanism simplified and rendered more flexible. A further object of my invention is to provide an improved feeding mechanism adapted to feed a mining machine laterally across a face either in one direction or in the opposite direction and one which is equally well adapted for use with a plurality of flexible feeding elements or with a single flexible feeding member. These and further objects and advantages of my invention will, however, hereinafter more fully appear.

In the accompanying drawings I have shown for purposes of illustration two embodiments which my invention may assume in practice.

In these drawings,—

Fig. 1 is a plan view of the more copiously illustrated embodiment of my invention with parts broken away to show details of the mechanism, the same being embodied in a cable propelled machine utilizing a plurality of cables.

Fig. 2 is a view partially in side elevation and partially in central vertical longitudinal section through the machine shown in Fig. 1.

Fig. 3 is a plan view of such a machine designed for use with a single continuous flexible feeding member.

Figs. 4 and 5 are side elevations of the rear portions of the machine frame shown in Fig. 3.

In view of the fact that the feeding mechanism is generically the same in both the illustrative forms disclosed herein, I will describe this mechanism in connection with Figs. 1 and 2. In these figures it will be observed that the mining machine comprises a machine frame 1 slideable on its bottom 2 on the mine bottom and carrying a cutter bar 3 which, as is customary in a room and pillar machine, projects in a horizontal plane from the front end of the machine and carries a cutter chain 4 movable about the bar by means of a cutter chain driving sprocket 5 carried on the frame

1 and herein disposed beneath the same at a point slightly nearer the rear end thereof. This cutter chain driving sprocket 5 is herein driven through connections later described from a suitable motor 6 carried on the frame, herein a longitudinally disposed horizontal electric motor carried on the front end of the frame. As shown, the frame also carries feed operating and controlling mechanism in the form of drums 7 and 8 adapted to cooperate with flexible feeding portions 9 and 10 respectively, herein in the form of separate cables wound on the drums and driving connections between the drums and motor hereafter described, whereby when the flexible feeding portions are extended from the drums to the opposite ribs in the mine around suitable guiding means in the form of sheaves 11 and 12, the machine may propel itself transversely across the face to be cut.

Now taking up this structure more specifically, it will be observed that the rear end of the armature shaft of the motor 6 carries a pinion 13, herein a bevel pinion meshing with a larger bevel gear 14 mounted upon an upright shaft 15 suitable journaled at 16 on bearings on the frame 1 and that this shaft 15 carries on its lower end a spur pinion 17 meshing with a larger spur gear 18 which is as usual operatively connected through suitable clutch mechanism, not shown, to the cutter chain driving sprocket 5. Obviously, through the driving train just described the cutter chain may be driven by the motor whenever it is desired; and, depending upon the direction of rotation of the motor, it may be driven in either direction about the cutter bar. Operatively connected to the gear 18 and rotatable thereby is a train of mechanism driving the feeding mechanism. As shown, this mechanism includes an upright shaft 19 suitably journaled as at 20 on the frame 1 and carrying on its upper end a bevel pinion 21 which meshes with a pair of oppositely disposed larger bevel gears respectively numbered 22 and 23 coaxially journaled in suitable bearings coaxial with a shaft 24. Herein the gear 22 is adapted to be connected to the shaft 24 through a friction clutch 25 having one series of elements connected to the shaft 100

as through a member 26 and the other fixed to the gear as at 27. The gear 23 is adapted to be connected to the shaft 24 through a friction clutch 28 part of whose elements are connected to the shaft 24 through an element 29 keyed to the shaft and the remainder are connected as at 30 to the gear 23. Disposed upon the shaft 24 between these elements is a collar member 31 having projecting from the opposite sides thereof series of fingers 32 and 33 which are respectively adapted to effect engagement of the friction clutch 25 and the friction clutch 28 so that the shaft 24 may be driven by the gear 22 or the gear 23. For the purpose of moving the collar or sleeve 31 longitudinally of the shaft in opposite directions a suitable shipper fork 35 is secured upon a vertical shaft 36 extending through the top cover 37 of the frame and actuatable by a lever 38.

20 The armature shaft of the motor carries immediately forward of the pinion 13 a spur pinion 40 meshing with a larger spur gear 41 which is secured to a short shaft 42 which 25 provides a bearing for a reduced portion 43 of the shaft 24, the shaft 42 being suitably journaled at one end as at 45 while its other end 46 is secured within a sleeve-like portion 47, more fully described hereafter, which is 30 journaled in a bearing 48. The sleeve portion 47 is secured to and formed integral with a friction clutch housing 49 within which friction elements 50 and a sleeve 51 keyed to the shaft are arranged, certain of the friction elements being mounted in non-rotative relation with respect to the housing 49 while others are similarly mounted with respect to the element 51. For the purpose of effecting engagement of this friction clutch a collar 52 35 having fingers 53 adapted to press the friction discs into engagement is slidably longitudinally of the shaft 24, suitable means for sliding it of well-known type including a lever 55, a shaft 56 and a fork 57, being provided.

40 By virtue of the mechanism so far described, it will be evident that the shaft 24 can be driven in opposite directions at a relatively slow speed and in one direction at a relatively fast speed without reversal of the motor, while, by reversing the motor, drive in both directions at a slow speed may still be obtained, while a fast rotation of the shaft in the opposite direction is securable.

45 Adjacent its rear end, between suitable bearings 60 and 61, the shaft 24 carries a worm 62 which meshes with and drives a large worm wheel 63, which is supported upon housing members 64 and 65 bolted thereto and journaled respectively in bearings 66 and 67 which surround sleeve portions 68 and 69 respectively formed integral with the members 64 and 65. Journaled within the sleeves 68 and 69 are a pair of oppositely disposed bevel gears 71 and 72 mounted upon the polygonal ends 73 and 74 of shafts 75 and 76,

which last are positioned at the sides of the frame respectively by bearings 77 and 78 in which are journaled the hubs 79, of which but one is shown, of pinions 81 and 82, respectively keyed to the shafts 75 and 76. Between the gears 71 and 72 and carried upon pivots 83 mounted on pivot pins projecting from a ring 85 is a series of gears 86 which mesh with the gears 71 and 72 and make up with these gears a differential, this term being here used in the sense which is customary in connection with automobile transmissions. It will be observed that to the shaft 75 a brake drum 90 is secured and that a similar brake drum 91 is secured to the shaft 76 and it will be observed, moreover, that suitable manually controllable brakes 92 and 93 are provided together with controlling means 94 and 95 therefor for the purpose of permitting the braking of the rotation of the shafts 75 and 76. It will herein be evident that the brakes 92 and 93 may cooperate directly with the drums 7 and 8 if desired, there being provided under such circumstances braking surfaces on the drums. It will be noted, moreover, that the drums 7 and 8 are journaled upon suitable bearings, of which one is shown at 97, and these drums include suitable rope winding surfaces 98 and 99 and internal gears 101 and 102 which mesh with and are adapted to be driven by the pinions 81 and 82 upon the shafts 75 and 76. It is to be noted that guiding sheaves 11' and 12' are arranged in suitable positions at the opposite sides of the machine frame so that by a reversal of the connection and the reeve of the flexible portions 9 and 10 the machine may, when the cutter bits have been reversed and the motor reversed, cut in the opposite direction.

50 Before describing the operation of the mechanism so far disclosed, I shall describe a second form which this invention may assume in practice, which form is primarily adapted for use with a continuous flexible feeding member, but which by certain substitutions of parts may be employed with the pair of separate flexible cables shown in the first form of the invention. This second form is shown in Figs. 3 to 5 of the drawings. In this form of the invention a chain 110 is used, which chain is adapted to extend about certain cooperating chain engaging elements on the machine frame and to be secured at its opposite ends to certain jacks or take-up members adjacent the opposite ribs or at other suitable points. In this form the pinions 81 and 82 are replaced by driving sprockets 111 and 112 mounted upon the shafts 75 and 76 respectively and the drums 7 and 8 and the journaling means therefor are omitted, although it is to be understood that openings 113 and 114 are provided, which openings are adapted to permit the mounting of the drums and their journaling means upon the frame if desired. For the

purpose of permitting the presence of a certain amount of slack between the sprockets 111 and 112 a channel 115 is extended across the rear end of the frame so that it may serve as a guiding means for the slack in the chain. This channel may, however, be replaced by other suitable guiding means as, for example, additional sprockets if desired. Arranged respectively at the front left hand and rear right hand corners of the frame are guiding sprockets or sheaves 116 and 117 and corresponding sprockets for use during cutting in the opposite direction may be arranged respectively at the remaining front and rear corners as shown at 118 and 119. As to these guide sheaves and the sprockets, it is to be observed that they may be replaced by ordinary guide pulleys or sheaves with half round or similar grooves if it is desired to convert the machine to a two cable flexibly fed type. For the purpose of guiding the chain 110 during feeding, additional guide sprockets are arranged at the sides of the frame, one of these being shown at 120 below and forward of the sprocket 112. Another is arranged above and slightly forward of this sprocket and is illustrated at 121. At the opposite side of the machine no auxiliary guiding sprocket is requisite in cutting from right to left. The manner of reeving the chain during cutting from right to left is as follows:—The chain is led from a suitable jack at the left hand rib and fairly close to the face about the sprocket 116, beneath the sprocket 120 about the rear of the sprocket 112, up over the front of the sprocket 121, through the guide 115, over the top of sprocket 111 and around the sprocket 117, to the right hand rib where it is connected to another jack or take-up mechanism if desired. For the purpose of permitting this form of the machine to cut from left to right as well as from right to left, additional openings are provided at 122 and 123 so that the sprockets 120 and 121 may be moved from their positions on the left hand side of the machine and disposed upon the right hand side of the latter, their holding means co-operating with these auxiliary openings at that time.

From the description given it will be readily apparent that by suitable variation in the position of the sprockets 120 and 121 this machine may be caused to cut in either direction across a face, it being understood that either the sprocket 116 or the sprocket 119 and correspondingly the sprocket 117 or sprocket 118, depending upon which direction cutting is being done, may be left off. It will also be evident that by reason of the presence of the openings 113 and 114 and the removability of the driving and power sprockets 111 and 112 the machine may readily be converted to the form shown in the first form of my invention illustrated in Figs.

1 and 2, by the addition of the drums 7 and 8 and the substitution of the pinions 81 and 82 for the sprockets 111 and 112, together with the substitution of suitably grooved sheaves for the guide sprockets. It is thus apparent that a machine capable of cutting in either direction and capable of employing either a continuous flexible feed chain or a pair of separate feeding and guiding cables is provided.

Now taking up the mode of operation of the form of my invention which has been first described, namely, the cable feed form, and assuming that the machine is at the center of the entry and about to make a cut, it will be evident that the cable 9 may be led back from the guide 11 around the guide 12' and thence to a jack or take-up mechanism adjacent the right hand rib, but spaced from the face a distance about equal to the length of the mining machine frame. The necessary slack may be obtained either by taking the cable from the drum by hand, or, better, by locking the member 91 and by suitable manipulations of the motor controller and clutches, causing the drum 7 to pay off the necessary cable. The machine may then be moved to the summing position, if the bottom is very smooth, at the fastest speed, that is, the feed controlled by the friction clutch 50, or if the bottom is rougher and more power is required, by the slower feed, but as in either event the brake band 93 will lock the shaft 76 against rotation and so hold the gear 72 against rotation, there will be a substantial saving in time during this operation of moving the machine up to position ready to begin summing. When the machine reaches the pre-summing position the rope 9 may be disengaged from the sprocket 12' and the rope 10 having been unwound from the drum 8 in any desired manner may be led over to a jack at the left hand rib and close up to the face and passed around the guide sheave 12. The cutter chain driving clutch, referred to above but not disclosed, may be then used to start the rotation of the cutter chain and the machine may be sumped in, depending upon the softness or hardness of the coal, either by the fast or the slower feed mechanism, but even by the latter at approximately twice the speed at which the machine will cut when going across a face, it being understood that the clutch 50 will be actuated if very fast summing is possible, while the clutch 28 will be actuated if a slower summing speed is desirable, that the brake band 93 will be used to hold the member 91 and accordingly the gear 72 against rotation during summing at either speed. The pinion 40 will drive the gear 41 and the pinion 21 the gear 23, and either drive may rotate the worm 62 clockwise when viewed from the rear end of the machine. This will cause clockwise rotation of the worm wheel 63 in Fig. 2 and clockwise

rotation of the shaft 75 at twice the speed of angular rotation of the gear 63. This will cause the pinion 81 to drive the gear 101 in such direction as to effect winding in of the cable 9 by the drum 7. It will be understood that a different method of summing can be used if desired. The machine may be placed at a greater initial angle to the rib and summed in under the joint control of both 10 brake bands, the feed drum paying out and the take-up drum drawing in, and the frictions being manipulated to "swing" the bar under the coal, so to speak. After the summing cut has been completed, the machine may 15 be straightened up perpendicular to the face by locking the brake drum 90 and by engaging the clutch 25 and throwing out the clutch 28, causing the drum 8 to wind in the member 10, while the tail rope 9 remains of constant length. When the machine has been 20 brought into the desired relation to the face for the transverse cut, the clutch 25 remaining in engagement and the drive being through the pinion 13, gear 14, pinion 17, gear 18, pinion 21, gear 22, shaft 24, worm 25 62, worm wheel 63, etc., the shaft 76 will, provided the resistance to rotation of the shaft 75 be made equal to the resistance to rotation of the shaft 76, cause the machine to proceed 30 across the face while remaining perpendicular thereto. It will be evident that with the reeve shown the pull of the tail rope will be in a direction to cause the shaft 75 to rotate in the direction in which it would normally be driven by the drive mechanism and 35 accordingly with no load upon the brake drum member 90 the machine would not move at all for, since a pull of several tons is necessary to propel the machine across the face, a considerable resistance would be opposed 40 to the rotation of the gear 72 while the gear 71 would be entirely free to unwind substantially without any resistance. It is accordingly necessary to tighten the brake band 92 to such an extent that it will oppose a resistance 45 to turning of the shaft 75 equal to the resistance opposed to the turning of the shaft 76 during feeding across a face. The further phases of the operation of this machine need 50 not be considered in detail for they will be obvious to one skilled in this art from what has been described so far. It will be evident, however, that there is provided a machine which can be handled with great facility and 55 that simply by adjusting the friction bands 92 and 93 the movements of the machine may be very readily controlled, it being necessary in fact only to control the brake band 92 when cutting across the face for, if it is desired 60 that the rear end of the frame should lag somewhat, the brake band 92 may be tightened still further so that the tail rope will not be paid out as rapidly while the cable 10 will be wound in more rapidly, while, if 65 it is desired to have the rear end of the frame

gain on the point of the cutter bar, this can readily be accomplished by simply slackening the tension of the brake band 92, for then the tail rope will pay out more rapidly than the rope 10 is wound in and so the rear end of the machine will move ahead faster than the cutter bar. It will be evident that the rear end of the machine may be pulled back in cutting around a sulphur ball by the proper use of the reversing clutches, etc. The further advantageous potentialities of this mechanism will readily suggest themselves to one skilled in the art and accordingly it is believed unnecessary to increase the length of this description by a further analysis of the different cutting operations possible. It may simply be said in conclusion, however, that, as pointed out above, the cutter bits having been reversed in the chain and the motor reversed, the machine may obviously be controlled so that by proper reeving of the ropes 9 and 10 it may cut from left to right. It will further be noted that the cables 9 and 10 may extend directly from the drums and around angularly disposed sheaves in place of sheaves 11' and 12'. 70 75 80 85 90 95

While I have in this application specifically described two forms which my invention may assume in practice, it will be understood that these forms of the same are shown for purposes of illustration and that the invention may be modified and embodied in various other forms without departing from its spirit or the scope of the appended claims. 95

What I claim as new and desire to secure by Letters Patent is: 100

1. In a mining machine, the combination including a motor, and flexible feeding means driven thereby including a plurality of flexible feeding portions extending oppositely laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, and a reversible power connection with the third coaxial element for driving the latter selectively in opposite directions while said motor runs continuously in the same 105 110 115 120 125 direction.

2. In a mining machine, the combination including a motor, and flexible feeding means driven thereby including a plurality of flexible feeding portions extending oppositely 130

laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said members and another of which provides orbitally moving means which constitutes a connecting means between said coaxial portions, operative connections between one of said coaxial elements and one of said members, distinct operative connections between another of said members, means for retarding the rotation of one of said last mentioned coaxial elements, and a reversible power connection with the third coaxial element for driving the latter selectively in opposite directions while said motor runs continuously in the same direction.

3. In a mining machine, the combination including a motor, and flexible feeding means driven thereby including a plurality of flexible feeding portions extending oppositely laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of either of said two last mentioned coaxial elements, and a reversible power connection with the third coaxial element for driving the latter selectively in opposite directions while said motor runs continuously in the same direction.

4. In a mining machine, the combination including a motor, and flexible feeding means driven thereby including a plurality of flexible feeding portions extending oppositely laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting

means between said coaxial portions, operative connections between one of said coaxial elements and one of said members, distinct operative connections between another of said coaxial elements and another of said members, and a power connection with the third coaxial element including fast and slow speed driving connections therefor, said power connection including means for effecting rotation of said third coaxial element in opposite directions without reversing said motor.

5. In a mining machine, the combination including a motor, and flexible feeding means driven thereby including a plurality of flexible feeding portions extending oppositely laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of one of said last mentioned coaxial elements, and power connections with the third coaxial element including fast and slow speed driving connections therefor, said power connections including means for effecting rotation of said third coaxial element in opposite directions without reversing said motor.

6. In a mining machine, the combination including a motor, and flexible feeding means driven thereby including a plurality of flexible feeding portions extending oppositely laterally from the opposite ends of a machine during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of either of said two last mentioned coaxial elements, and power connections with the third coaxial element including fast and slow speed driving connections therefor, said power connections including means for effecting rotation of said third coaxial element in opposite directions without reversing said motor.

tion of said third coaxial element in opposite directions without reversing said motor.

7. In a mining machine, the combination including a motor, and flexible feeding means driven thereby including a plurality of flexible feeding portions extending oppositely laterally from the opposite ends of a machine during cutting across a face, rotatable members operatively engaging said portions and 5 respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of either of said two last mentioned coaxial elements, and a 70 power connection with the third coaxial element including fast and reversible slow speed driving connections therefor for driving said latter element at a fast speed in one direction and at a slow speed in opposite directions 75 while said motor runs continuously in the same direction.

10 8. In a mining machine, the combination including a motor, and flexible feeding means driven thereby including a plurality of flexible feeding portions extending oppositely laterally from the opposite ends of a machine 15 during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means 20 between said coaxial portions, operative connections between one of said coaxial elements and one of said members, distinct operative connections between another of said coaxial elements and another of said members, means for retarding the rotation of one of said last 25 mentioned coaxial elements, and a power connection with the third coaxial element including fast and reversible slow speed driving connections therefor for driving said latter element at a fast speed in one direction and at a slow speed in opposite directions while 30 said motor runs continuously in the same direction.

35 9. In a mining machine, the combination including a motor, and flexible feeding means driven thereby including a plurality of flexible feeding portions extending oppositely laterally from the opposite ends of a machine during cutting across a face, rotatable members operatively engaging said portions and 40

45 respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of either of said two last mentioned coaxial elements, and a 50 power connection with the third coaxial element including fast and reversible slow speed driving connections therefor for driving said latter element at a fast speed in one direction and at a slow speed in opposite directions 55 while said motor runs continuously in the same direction.

60 10. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members, and reversible power connections with the third coaxial element for driving the latter selectively in opposite directions while said motor runs continuously in the same direction. 65

70 11. In a mining machine, the combination including flexible feeding means including a motor, and a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members, and fast and slow speed power connections with the third co- 75

axial element including means for reversing the direction of rotation of said third coaxial element without reversing said motor.

12. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members and fast and reversible slow speed power connections with the third coaxial element for driving the latter at a fast speed in one direction and at a slow speed in opposite directions while said motor runs continuously in the same direction.

13. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and reversible power connections with the third coaxial element for driving the latter selectively in opposite directions while said motor runs continuously in the same direction.

14. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving

gear means having teeth moving at equal angular rates constituting a connection between said coaxial gears, operative connections between one of said coaxial elements and one of said members, distinct operative connections between another of said coaxial elements and another of said members, and fast and slow speed power connections with the third coaxial element including means for driving the latter selectively in opposite directions while said motor runs continuously in the same direction.

15. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and fast and reversible slow speed power connections with the third coaxial element for driving the latter at a fast speed in one direction and at a slow speed in opposite directions while said motor runs continuously in the same direction.

16. In a mining machine, the combination including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, means for retarding the rotation of one of the two last mentioned coaxial elements, and reversible power connections with the third coaxial element for driving the latter selectively in opposite directions while said motor runs continuously in the same direction.

17. In a mining machine, the combination

including a motor, and flexible feeding means driven thereby including a plurality of flexible feeding portions extending oppositely laterally from the opposite ends of the machine during cutting across a face, rotatable members operatively engaging said portions and respectively operative when rotated in the proper direction to draw in the portions with which they cooperate, and mechanism 10 for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, means 15 for retarding the rotation of one of the two last mentioned coaxial elements, and fast and reversible slow speed power connections with the third coaxial element for driving the latter at a fast speed in one direction and at a 20 slow speed in opposite directions while said motor runs continuously in the same direction.

18. In a mining machine, the combination including a motor, and flexible feeding means 30 driven thereby including a plurality of flexible feeding portions extending oppositely laterally from the opposite ends of the machine during cutting across a face, rotatable members operatively engaging said portions and 35 respectively operative when rotated in the proper direction to draw in the portions with which they cooperate, and mechanism for controlling the rotation of said members including three coaxial elements, two providing coaxial gears and the third orbitally moving gear means having teeth moving at equal angular rates constituting a connection between 40 said coaxial gears, operative connections between one of said coaxial elements and one of said members, distinct operative connections between another of said coaxial elements and another of said members, means for retarding the rotation of either of said two last 45 mentioned coaxial elements including adjustable frictional retarding means, and reversible power connections with the third coaxial element for driving the latter selectively in opposite directions while said motor runs continuously in the same direction.

55. 19. In a mining machine, the combination including a motor, and flexible feeding means driven thereby including a plurality of flexible feeding portions extending oppositely laterally from the opposite ends of the machine 60 during cutting across a face, rotatable members operatively engaging said portions and respectively operative when rotated in the proper direction to draw in the portions with which they cooperate, and mechanism for 65 controlling the rotation of said members in-

cluding three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, means for retarding the rotation of either of said two last mentioned coaxial elements including adjustable frictional retarding means, and fast and reversible slow speed power connections with the third coaxial element for driving the latter at a fast speed in one direction and at a slow speed in opposite directions while said motor runs continuously in the same direction. 70 75 80

20. The combination with a mining machine, of a feed operating mechanism therefor including a motor, a differential including elements movable in an orbit upon transmission of power thereto by said motor, and means for driving said differential from said motor in a plurality of directions while said 85 motor direction remains the same. 90

21. The combination with a mining machine, of feed operating mechanism including a motor, a differential including elements movable in an orbit upon transmission of power thereto by said motor, and means driven by said motor for driving said differential in a plurality of directions while said motor runs continuously in the same direction including a plurality of driving trains. 95 100

22. The combination with a mining machine, of feed operating mechanism including a motor, a differential including elements movable in an orbit upon transmission of power thereto by said motor, and means driven by said motor for driving said differential in a plurality of directions while said motor runs continuously in the same direction including a plurality of driving trains and a clutch mechanism for each train operative to connect one train and disconnect the other. 105 110

23. The combination with a mining machine, of feed operating mechanism including a motor, a differential including elements movable in an orbit upon transmission of power thereto by said motor, and means driven by said motor for driving said differential in a plurality of directions while said motor runs continuously in the same direction including a plurality of driving trains and a single frictional mechanism for each train operative to connect or control said trains. 115 120

24. The combination with a mining machine including a motor, of cutting mechanism, feed operating mechanism including a differential including elements movable in an orbit upon transmission of power thereto by said motor, and means for driving said dif- 125 130

ferential at different speeds in different directions while said motor runs in one direction including a train driven from said cutting mechanism.

25. The combination with a mining machine, of cutting mechanism, feed operating mechanism including a differential including elements movable in an orbit upon transmission of power thereto by said motor, and means for driving said differential at different speeds and in different directions while said cutting mechanism operates continuously in the same direction and including a train driven from said cutting mechanism and a high speed train independent of said cutting mechanism.

26. The combination with a mining machine, of cutting mechanism, feed operating mechanism including a differential including elements movable in an orbit upon transmission of power thereto by said motor, and means for driving said differential at different speeds and in different directions while said cutting mechanism operates continuously in the same direction and including a train driven from said cutting mechanism and a high speed train independent of said cutting mechanism and a friction mechanism controlling each train.

30. The combination with a mining machine, of feed operating means thereon including a motor, a differential including elements movable in an orbit upon transmission of power thereto by said motor, worm and worm gear driving mechanism for said differential, and means for rotating said worm at different speeds and in different directions while said motor speed remains constant and the direction of motor rotation remains unchanged.

40. The combination with a mining machine, of feed operating means thereon including a motor and a differential including elements movable in an orbit upon transmission of power thereto by said motor, worm and worm gear driving mechanism therefor, and means driven by said motor for rotating said worm at different speeds and in different directions without reversing said motor and including a plurality of drive trains.

45. In a mining machine, the combination including flexible feeding means including a plurality of flexible feeding portions extending oppositely from the opposite ends of the machine during cutting across a face, rotatable feed operating and take-up members respectively operatively engaging said portions, a motor, a differential driven by said motor and having coaxial elements connected by orbitally moving elements, operative connections between one of said coaxial elements and said feed operating member, operative connections between another of said coaxial elements and said take-up member, means for braking the rotation of either said

feed operating member or said take-up member, and means for effecting orbital movement of said orbitally movable members including fast and slow speed driving connections, said slow speed driving connections being operative to effect rotation of said orbitally moving members in their orbit in either direction without reversal of the motor.

50. In a mining machine, the combination including flexible feeding means including a plurality of flexible feeding portions extending oppositely from the opposite ends of the machine during cutting across a face, rotatable feed operating and take-up members respectively operatively engaging said portions, a motor, a differential driven by said motor and having coaxial elements connected by orbitally moving elements, operative connections between one of said coaxial elements and said feed operating member, operative connections between another of said coaxial elements and said take-up member, means for braking the rotation of either said feed operating member or said take-up member, and means for effecting orbital movement of said orbitally movable members including fast and slow speed driving connections, said fast speed driving connection being operative to effect rotation of said take-up member in a direction to cause the same to draw in the flexible portion operatively connected thereto, and said slow speed driving connections being operative to effect rotation of said orbitally moving members in their orbit in either direction without reversal of the motor.

55. In a mining machine having reversible cutting mechanism, means for effecting controlled feeding of said machine in opposite directions transversely of a working face and for controlling the angle thereof during feed in either direction including a plurality of driving members, means for rotating said members in opposite directions, means for interchangeably supporting for driving by said members a plurality of sets of feed operating members including means on the machine for supporting either member, one set of said feed operating members being adapted to cooperate with a single flexible feeding member and the other set of which is adapted to cooperate with separate flexible feeding and trailing members, and means on the machine for supporting interchangeably a plurality of sets of guiding members adapted to cooperate respectively with a single flexible feeding member or with separate flexible feeding members.

60. In a mining machine having reversible cutting mechanism, means for effecting controlled feeding of said machine in opposite directions transversely of a working face and for controlling the angle thereof during feed in either direction including a plurality of driving members, means for rotating said

members in opposite directions, means for interchangeably supporting for driving by said members a plurality of sets of feed drums and driving sprockets including means on the machine for supporting either said drums or said sprockets, said set of driving sprockets being adapted to cooperate with a single flexible feed chain and said set of feed drums being adapted to cooperate with separate flexible feeding and trailing cables, and means on the machine for supporting interchangeably a plurality of sets of guiding sheaves and sprockets adapted to cooperate respectively with separate flexible cables or with a single flexible feed chain.

15 In testimony whereof I affix my signature.

MORRIS P. HOLMES.
